Atty.

UNITED STATES PATENT OFFICE.

THEODORE J. SMULSKI, OF CHICAGO, ILLINOIS.

TIMING DEVICE.

Application filed August 18, 1919. Serial No. 318,097.

To all whom it may concern:

Be it known that I, THEODORE J. SMULSKI, a citizen of Poland, residing at Chicago, in the county of Cook and State of Illinois, 5 have invented certain new and useful Improvements in Timing Devices, of which the following is a specification.

My invention relates to timing devices in which a firing spark is provided at the 10 proper time to ignite a gas mixture in the cylinder or cylinders of an internal combustion motor. And the object thereof is to provide a simple, cheap and effective device which shall be accurate and positive in its 15 action and in which the pressure of the moving contact device on the commutator shall be equalized at the varying speeds at which it is revolved.

The principles of my invention are illustrated in the drawings in which Fig. 1 shows 20 a front view of my device with the protective cap removed. Fig. 2 is a vertical section of my device on line 2—2 of Fig. 1. Fig. 3 is a rear view showing one form of 25 the moving contact mechanism. Fig. 4 is a section on line 4—4 of Fig. 2. Fig. 5 is a similar view showing another form of contact. Fig. 6 is a view on line 6—6 of Fig. 5. Fig. 7 shows the commutator mounting. 30 Fig. 8 is a perspective view of the lever of which a top view is shown in Fig. 6 and a side view is shown in Fig. 5.

Further describing my invention by reference to the drawings in which like characters of reference denote like parts throughout,

1 is the external shell of a commutator, an opening being made centrally to the face. The cut away portion is surrounded by an 40 annular insulation piece 2 secured upon the shell by means of rivets 3 or other suitable means. A commutator comprising an insulated portion 4 and the commutator bars 5 of any desired number is secured upon the 45 shell or casing by connections 6 which may be formed integrally with the commutator bars and provided with offset feet 7. Said feet pass through the opening in the face of the shell and beyond the annular insulation 50 2 and are secured in place thereon by means of the bolts 8 which pass through said insulating ring at the cut away points 10 in the metal casing. Clips 11 made to conform with the connection 6 and the foot 7 thereon 55 are adapted to act as clamps in conjunction

with said bolts 8 to secure the distribution lead wires 12. The engine timing shaft 15 is reduced in size at 16 to receive a sleeve 17 which is securely attached thereto by a nut 18 or other suitable means. Said sleeve is 60 provided with a radial arm 19 having a laterally extended flange at its end. Said sleeve passes through the commutator and is adapted to rotate together with its arm 19 out of electrical contact therewith. 65

A lever shown in one form in Figs. 5, 6 and 7 comprises two side pieces 25 held together by a bolt or rivet 26 which passes through the spacing piece 27 and also serves to secure said lever upon the arm 19. One 70 arm of said lever is provided with off-sets 28 between which and a retaining bolt 29 is held the brush 30 whose end 31 is adapted for frictional contact upon the outer face of the commutator. Said brush has a notch in 75 one face adapted to receive the bolt 29 which may be secured in place by means of cotter pin 31. When the said device is pivotally mounted on the arm 19 by means of the pivot bolt 26 the brush is held in normal 80 contact with the commutator by means of the spring 33 one end of which is attached to the flange 20 of arm 19 and the other attached at 34 to the other arm of said lever, the action of said spring being to hold the brush 85 in contact with the armature as it is revolved thereabout by the revolution of the timing shaft 15. The strength of the said spring should be adapted to a low speed of timing shaft. The tendency then will be to 90 make a lighter contact as the engine speed is increased. To counteract this I provide a counter weight 36 on the other end of the said lever the effect of which at all times is to keep the brush in complete contact with 95 the commutator.

An alternative form of brush is illustrated in Figs. 3 and 4 and provides a rolling contact instead of the sliding one just described. It consists of a wheel or roller 40 secured 100 between the side pieces of the contact lever by means of a pin 41 secured in place by means of cotter pin 42. But in either case the balancing action of the counter weight is the same. The protective cap 45 is adapted 105 to fit closely around the edges of the annular insulation 2 and means for advancing or retarding the spark comprises the external lever 45 to which should be attached the controlling rod 46 by which the casing 110

may be partially rotated to advance or retard the spark.

I claim:

1. In a timing device; a commutator, a sleeve passing through the commutator out of electrical contact therewith and adapted to be secured to a timing shaft, a radial arm on said sleeve, a contact carrying lever pivoted between its ends on said radial arm and revolvable about the commutator, a contact on one arm of the said lever normally adapted to bear on said commutator, and a counter weight on the other end of said contact carrying lever.
2. In a timing device; a commutator, a sleeve passing through the commutator out of electrical contact therewith and adapted to be secured to a timing shaft, a radial arm on said sleeve, a contact carrying lever pivoted between its ends on said radial arm and revolvable about the commutator, a contact on one arm of said carrier, spring means for normally holding said contact in operative relation to the commutator and a counter weight on the other arm of the said contact carrying lever.
3. In a timing device; a commutator, a sleeve passing through the commutator out of electrical contact therewith and adapted to be secured to a timing shaft, a radial arm on said sleeve, a contact carrying lever pivoted between its ends on said radial arm, revolvable about the commutator, a brush on one arm of said contact carrying lever, spring means for normally holding said brush in operative relation to the commutator and a counter weight on the other arm of the said contact carrying lever.
4. In a timing device; a commutator having commutator bars on its peripheral face, a sleeve mounted on the timing shaft, and insulatedly rotatable within the commutator, a radial arm having one end attached to the sleeve, and the other end extending beyond the peripheral face of the commutator, a lever pivoted between its ends on said radial arm, a contact carried by one

arm of said lever and a counterweight on the other arm of said lever.

5. In a timing device; a commutator, a sleeve mounted on the timing shaft of an engine and rotatable within the commutator, a radial arm on said sleeve having an off-set flange, a lever pivoted between its ends on said radial arm below said flange, a brush on one end of said lever, a counter weight on the other end of said lever, a spring to connect the counterweighted end of the lever to said off-set flange.

6. In a timing device; a casing having an opening in the top thereof, an annular insulating piece secured to said top concentric with said opening, a commutator in said casing comprising an insulating ring and a plurality of commutator bars, said bars having legs extended through the opening in the top of the casing and having feet bearing upon and attached to said insulating piece.

7. In a timing device; a casing having an opening in the top thereof, an annular insulating piece secured to said top concentric with said opening, a commutator in said casing comprising an insulating ring and a plurality of commutator bars, said bars having legs extended through the opening in the top of the casing and having feet bearing upon said insulating piece, clips cooperating with said feet, and bolts to secure said feet and clips to said insulating piece and to each other.

8. In a timing device a casing having an opening in the top thereof, an annular insulating piece secured to said top concentric with said opening, a commutator in said casing having the bars thereof attached to said insulating ring and a protective cap having flanges adapted to engage the peripheral edges of said annular insulating piece.

In witness whereof I have hereunto attached my signature at Chicago, Cook County, Illinois, this 1st day of August, 1919.

THEODORE J. SMULSKI.
